Atts.

UNITED STATES PATENT OFFICE.

ARCHIBALD HENRY MONTGOMERY JOHN WARD, OF MEREWORTH, NEAR MAIDSTONE, ENGLAND.

PISTON.

Application filed March 31, 1924. Serial No. 703,222.

To all whom it may concern:

Be it known that I, ARCHIBALD HENRY MONTGOMERY JOHN WARD, a subject of the King of England, residing at Mereworth, 5 near Maidstone, Kent, England, have invented certain new and useful Improvements in Pistons, of which the following is a specification.

This invention relates to the pistons of engines, preferably internal combustion engines, of the kind in which there is an external groove near the bottom of the skirt in which lies a ring that bears against the bottom of the groove as well as against the cylinder wall. In this type of piston this ring (which hereunder is termed a "bearing ring") in addition to functioning as an oil scraper, serves to relieve the skirt of contact with the cylinder wall, and it is particularly 20 useful where the skirt is of aluminium alloy or similar soft metal.

The object of the invention is to provide an improved construction which can be made shorter than usual and which will be 25 free from binding or from creating excessive friction, and which will not be subject to fractures of the skirt.

The manner of carrying out the invention is illustrated in the accompanying drawings, 30 in which—

Figure 1 is a central vertical section showing the preferred construction of piston,

Figure 2 is an enlarged view showing the ring and adjacent parts of the piston skirt, 35

Figure 3 is a horizontal section on the line 3—3 of Figure 1, whilst

Figures 4 and 5 are a side view and section of the skirt on an enlarged scale showing a detail,

Figure 6 is a section, and

Figure 7 a side elevation showing the application of the invention to a skirtless piston.

Like letters indicate like parts throughout 45 the drawings.

In the construction shown in Figures 1 to 5, the piston is chiefly of conventional form having a skirt A which is preferably slit vertically at a number of points B in the 50 well-known manner. The gudgeon pin bosses are shown at C and preferably, to prevent weakness at these parts, no slits are, as a rule, formed in the skirt on the faces of the piston containing these bosses, but between the bosses, i. e. on those faces which

receive the thrust from the connecting rod and are herein termed the "pressure faces," any suitable number of slits are made.

Near the bottom of the skirt is a land D which is of smaller diameter than the cylinder bore. In this land is formed a groove D², and in the groove is located the split bearing ring E. This bearing ring is of hard metal, such as cast iron, and its outside diameter is that of the cylinder bore, or within small limits less than the bore. The bottom of the ring, i. e. the face E² (Figure 2), bears against the bottom of the groove D² on the pressure faces of the piston, i. e. along the arcs between the gudgeon pin 70 bosses C. At a suitable distance along the other faces, i. e. the faces which contain the bosses C, the bottom of the groove is relieved or cut away as shown at D³ so that on these sides or faces the ring E does not bear 75 against the bottom of the groove. It is therefore free to yield slightly, but all the side thrust of the piston due to the connecting rod is taken by the ring when bearing against the bottom of the groove on the 80 pressure faces. It will be observed that the ring, instead of being rigid, is slightly resilient, as is very desirable. The ring is located against twisting by means of a peg F.

If desired a spring ring may be arranged 85 inside the skirt, to resist the compression of the ring E and the skirt, in the well-known manner.

Seeing that the piston must not project below the bottom of the cylinder at the bottom of the piston stroke, as otherwise the ring E would spring out of the cylinder mouth, the piston must generally be made shorter than is usually the case when a split skirt is used. As the piston heats up and 90 the skirt tends to expand radially outwards, this is prevented by the ring E, which, as has been described, not only bears against the cylinder wall, but bottoms at the specified places only on the groove D². For this 95 reason the skirt is split as this allows the expansion of the metal of the skirt to take place without any binding. On the pressure faces of the piston, i. e., those faces which receive the thrust from the connecting rod, the slits B can be comparatively long, but, on the sides on which are located the bosses C, only very short slits can be made, and I have found that, with a short piston, if the ring E bottoms in the groove the 100 105 110

whole way round, the tongues formed between the slits in the skirt below the gudgeon pin bosses actually break off. These fractures are due to the insufficient springiness of the skirt tongues at this part, and to the rapid change of section at these points which concentrates the stresses along lines below the gudgeon pin bosses. These fractures and excessive binding of the ring E 10 are prevented in the present invention by relieving the bottom of the groove at D² adjacent to the gudgeon pin bosses. In most cases also it is necessary or desirable, as stated, that there should be no slits in the 15 skirt on the sides which contain the gudgeon pin bosses.

It will be clear that, as the skirt is of considerably less diameter than the cylinder bore, and the ring E when in place and compressed is only equal to, or slightly less than, the cylinder bore, the skirt does not require to be compressed or reduced in diameter when the piston is being fitted to the cylinder, only the ring E requiring to be compressed as is usual.

In the construction shown in Figures 6 and 7, where the piston is of extreme shortness as it possesses no actual skirt, the wall is split at B in the same manner as in the 30 construction just described, and there is a relieved groove D² containing the bearing ring E, but this groove is located in the horizontal plane containing the gudgeon pin G. The pin is notched at the ends at G², and the ring E lies in these notches but it does not bear against the bottom of the notches. The ring E also prevents the gudgeon pin G from working sideways to such an extent as to come into contact with the cylinder 40 wall represented by the broken line Z, and it also prevents the ring from twisting.

A further feature arising from the provision of a clearance under the bottom of the ring on the faces containing the gudgeon pins, is that these parts of the piston are free to expand radially slightly without setting up any binding. As stated, with short pistons it is not possible, or advisable, to split the skirt near the gudgeon pin bosses. 45 Consequently a great deal of the expansion of the metal which takes place at these points must be radially outwards. If the piston ring beds in the groove the whole way round, this outward expansion causes the ring to be pinched between the piston skirt and the cylinder wall, which clearly causes binding and, in severe cases, actual seizure.

An alternative to relieving the bottom of the groove is, of course, to make the ring thinner on those parts which lie on the faces containing the gudgeon pins. Where the ring is pinned to prevent its rotation it would be a simple matter to keep the thin parts of the rings in the required positions. 65 It is, however, preferable to increase the depth of the grooves rather than to thin the ring at two points.

What I claim as my invention and desire to secure by Letters Patent of the United States is:—

1. The combination with an engine piston of a split bearing ring thereon which has a clearance from the piston on the non-pressure faces only of the piston. 75

2. In a piston, the combination of a skirt, longitudinal slits in said skirt, a groove encircling the skirt, and a split bearing ring in said groove and bottoming therein only on the sides forming the pressure faces of 80 the piston, substantially as set forth.

3. In a piston, the combination of a skirt, longitudinal slits in said skirt, a groove encircling the skirt, and a split bearing ring located in said groove and bottoming therein 85 except on those sides of the piston which contain the gudgeon pin bosses.

4. In a piston, the combination of a skirt, a groove encircling said skirt, a bearing ring located in said groove and bottoming therein 90 only on the sides forming the pressure faces of the piston, and longitudinal slits in those sides only of the skirt which form the pressure faces, substantially as set forth.

5. In a piston, the combination of a skirt, 95 longitudinal slits in said skirt, a groove of varying depth encircling the skirt, and a split bearing ring located in said groove and bottoming therein only on the sides forming the pressure faces of the piston, substantially 100 as set forth.

6. In a piston, the combination of a groove extending around it in the plane of the gudgeon pin, a split bearing ring located in said groove bottoming only upon the sides 105 forming the pressure faces of the piston, and notches formed in the ends of the gudgeon pin which are engaged by said bearing ring, substantially as set forth.

In testimony whereof I have signed my 110 name to this specification in the presence of two subscribing witnesses.

ARCHIBALD HENRY MONTGOMERY JOHN WARD.
